(57) **CLAIM**

I claim the ornamental design for an electrical receptacle housing, as shown and described.

DESCRIPTION

FIG. 1 is a perspective view illustrating my new design of an electrical receptacle housing;

FIG. 2 is a top view thereof;

FIG. 3 is a front view thereof;

FIG. 4 is a side view thereof, the opposite side being a mirror image;

FIG. 5 is a rear view thereof; and,

FIG. 6 is a bottom view thereof.

The broken lines shown in FIGS. 1-4 and 6 are for illustrative purposes only and form no part of the claimed design.
